UNITED STATES PATENT OFFICE.

JOHN HENRY BARTELS, OF CHICAGO, ILLINOIS.

BALLOT BOX.

Application filed January 10, 1924. Serial No. 685,399.

To all whom it may concern:

Be it known that I, JOHN HENRY BARTELS, a citizen of the United States, residing at Chicago, in the county of Cook and State 5 of Illinois, have invented certain new and useful Improvements in Ballot Boxes, of which the following is a specification, reference being had to the accompanying drawings, and to the reference characters marked 10 thereon, which form a part of this specification.

This invention relates to ballot boxes and more particularly to a ballot box provided with an opening in its top through which 15 the ballot is to be inserted and which opening is covered by a hinged lid, operable by means within the box.

One of the objects of the invention is to produce a ballot box into which the voter 20 will not be permitted to insert a ballot, in the act of voting, except in connection with and in the presence of a judge or other election official, who will first manipulate the ballot box so as to uncover the opening.

Another object is to produce a ballot box 25 in which the ballot, when inserted in the opening, will not drop freely into the box, but will be drawn into the box by means of the pair of rollers manipulated by the election official.

Another object is to produce a ballot box 30 wherein the operating device which uncovers the opening through which the ballot is inserted and the device which completes the deposit of the ballot into the box will 35 also close the opening as soon as the deposit of the ballot has been effected. In other words, I propose to produce a ballot box which is locked; which will be opened when a voter presents himself to deposit 40 a ballot; which will deposit the ballot through mechanical means when the ballot is delivered in the opening by the voter and which will then be closed so that the ballot box will be in a locked position when the 45 next voter appears, the entire operation being controlled by the election official.

Another object of my invention is to automatically emboss, mark or indent each 50 ballot as it is being deposited in the box.

Another object of my invention is to produce a ballot box having ballot depositing mechanism therein, so arranged that it may 55 be operated by differently fashioned operating keys, so that in the event that one election official should attempt to prevent

proper voting by withholding an operating key in his possession and refusing to operate the ballot box mechanism, another official having a key may act.

Another object is to produce a ballot box 60 which will safeguard the "purity of the ballot" by a construction which will not permit of its being tampered with without the unauthorized act being detected.

These and other objects of the invention 65 will be more fully comprehended as I proceed with my specification.

To the above ends, my invention consists 70 in the devices and combinations of devices herein illustrated, described and more particularly pointed out in the appended claims.

One form of my invention is illustrated 75 in the accompanying drawing, in which Figure 1 is a perspective view of a sample ballot box embodying my invention.

Figure 2 is a bottom plan view, enlarged, 80 of the insert plate in the top of the ballot box, with the housing removed to disclose certain operative mechanism.

Figure 3 is a side view of the insert plate 85 in the plane indicated by the dotted line 3—3 on Fig. 2, showing one of the rollers in elevation, and the housing partly in section, looking in the direction indicated by the arrows.

Figure 4 is an end view of the insert plate 90 with the housing in section, as indicated by line 4—4, Fig. 2.

Figure 5 is a side view similar to Figure 3, showing the other roller in elevation, as indicated by line 5—5, Fig. 2.

Figures 6 and 7 are transverse vertical 95 sectional views of the insert plate, the sections being taken in the vertical planes, indicated by dotted lines 6—6 and 7—7, on Fig. 2, respectively.

Figure 8 is a similar view, the section 100 being in the vertical plane indicated by the dotted line 8—8 on Fig. 2, this view also showing a paper ballot being inserted in the box between the rollers.

Figure 9 is an enlarged sectional view 105 of the locking pin, the section being taken longitudinally on the vertical dotted line indicated at 9—9 on Fig. 4.

Figure 10 is a detailed view partly in section, enlarged, showing one of the operating handles.

Figures 11 and 12 are end views of the 110 two operating handles.

Figure 13 is a plan view, enlarged, of

a portion of the insert plate with the hinged lid open to reveal the ballot receiving rolls and the counting device.

Referring to the drawings, the ballot box 5 A, as a whole, may be of the shape illustrated in Fig. 1 comprising a body portion 1, and a top or cover portion 2, securely locked together by the padlock 3 or any suitable means. The top 2 will be provided 10 with a slot or opening 4 through which the ballot may be inserted. In this form here shown, the slot 4 is in an insert plate B secured in the top 2 and is covered by a hinged lid or cover 5, as shown more 15 clearly in Fig. 8.

A pair of rolls C, C, revolvably mounted on shafts 6—6* depend from the plate B and are adapted to be rotated towards each other so as to draw a ballot, indicated at 20 D, between them, when the latter is inserted through the slot 4, as shown in Fig. 8.

The shafts 6 are mounted in suitable bearings 7 and at one end each carries a gear 8. These gears intermesh so that the rotation 25 of one with its shaft and roll C will cause the other shaft 6 and its roll C to also rotate. The ends of these shafts 6—6* are differently shaped to fit the differently formed shaft sockets 9 and 10 in the ends 30 of the two operating wrenches EE, as shown in Figs. 11 and 12. These shaft ends 11 are preferably brought close to one end of the ballot box so as to be readily accessible of operation by the wrenches EE 35 through openings 12. Each wrench E may be provided with a hollow handle portion 13, closed by a suitable cap 14, so as to provide a convenient receptacle for a key F, different keys being provided for 40 judges of election of opposing political parties—as for example, Republican and Democrat. The keys F, F, are adapted to fit the locks 15—15, which locks hold the hinged lid 5 in place when closed; a slotted 45 hasp 16 being on the lid 5 adapted for engagement with the bolt 17 of the locks 15.

On the shafts 6 is a ratchet wheel 18, the teeth 19 of which are engaged by a pawl 20 pivoted at 21 to a bracket 22 on the 50 plate B. A bent spring 23 secured to the pawl 20 bears with its free end upon the plate B thus holding the pawl 20 under proper tension in constant engagement with the ratchet wheel 18. It will be seen 55 therefore that this shaft 6 and its gear 8 and roll C has a rotative movement, always in the same direction. A similarly arranged ratchet wheel 24 and spring pressed pawl 25 applied to the shaft 6* performs the 60 same function, i. e. of preventing this second shaft from rotation except in one direction.

Secured to the hinged lid 5 and extending therefrom through a slot in the plate B is 65 a curved arm 36, the free end of which is

pivotaly united to one end of a toggle link 27. One end 28 of a second toggle link 29 is pivoted to link 27 and the other end of link 29 being pivotally mounted in bracket 30 secured to plate B.

When a ballot, indicated at D, is to be voted the official by turning the handle 13 raises the lid 5 exposing the opening 4. The voter deposits the ballot through the opening until its end or edge is caught in the bite between rollers C, C, and as the official continues to manipulate handle 13 the rollers draw the ballot between them and deposit within the ballot box, and the lid 5 again closing the opening 4. In thus passing between the rollers, the ballot sheet is embossed so as to reveal the fact that it was a sheet actually voted. This is accomplished by slightly raised protuberances 26 on the rolls, of any suitable construction. 85 In this instance, said protuberances 26 are the rounded heads of screws set here and there in the rolls.

G is the counter device, as a whole, of any suitable or standard construction provided with marginally numbered rotatable discs so arranged as to register, one at a time, the number of ballots deposited within the box. This device G is secured to the underside of the plate B, by screws, or otherwise, so as to be visible through an opening a in the plate, as shown in Fig. 13. It is provided with a rotatable operating shaft 40 carrying ratchet wheel 31.

A pawl 41 engages the ratchet wheel 31 and a friction spring 32 secured to the plate 5 also engages this wheel (as shown in Fig. 6), the pawl to rotate always in the same direction the wheel 31 one notch or tooth at a time and the other to hold the wheel 31 in position.

The pawl 41 reciprocates through a guide-way 33 and is pivotally attached at 34 to a rocker arm 35, the upper end of which is swingingly mounted in the bracket 30 on the plate 5. A tension spring 37 bears against the arm 35. The lower end of the rock arm 35 engages a cam groove 38 in a cam 39 mounted upon the shaft 6* which rotates one of the rolls C. Thus when the roller shaft 6* has made one complete revolution the cam will have rocked the arm 35 first in one direction and then in the other, back to its starting position, the arm 35 will have given the pawl 41 its proper reciprocative movement, the latter will have rotated the ratchet wheel 31, and the appropriate rotative movement will have been given to the counter device operating shaft 40, whereby the numerals visible through the opening a of plate 5 will register a higher total, by one, than was previously registered.

In order to compensate for ballots of varying thickness, I find it desirable to 130

provide that one of the rollers C may yield somewhat and this I accomplish in the following manner.

One end of the shaft 6 is mounted in a movable bearing box 42 so as to slide laterally in a guide way frame 43. A tension spring 44 is placed within the frame 43 so that one end may bear upon the box 42 and in its normal position hold the box 10 towards the center of the device, whereby the two rolls are in closed ballot gripping position, and whereby the rolls may be slightly separated by the compression of spring 44.

15 The gear 8 or shaft 6 is provided with a recess 45 to receive the end of a locking bolt 46 which passes through a spring contained hub 47 on the housing wall 48. By pulling on the handle 49 the spring 50 is compressed by the collar 51 on the bolt 46 and the bolt 46 moved lengthwise until its end is free from the gear, thus permitting the latter to rotate. When handle 49 is released, the spring 50 forces the bolt in 20 the other direction to lock the gear. 52 is a suitable metal housing secured by rivets 25 53 or otherwise to the plate B.

From the foregoing description, it will be understood that in using the ballot box, 30 the election authorities will first record the reading register and then lock the cover on the empty box. When returned by the official of the polling place or precinct where it has been used, the reading on the counting device will show the total number of 35 ballots cast at that election, and this number should tally with the number of ballots actually within the box. Every ballot cast will have been embossed by the rollers C, 40 and hence any attempt to change the result by adding an unauthorized ballot or by substituting such a ballot for one actually voted, may be readily detected.

It will also be understood that before 45 the box may be put into use at the polling place both election officials must be present and each unlock the proper lock 15 with his appropriate "party" key F. Thereafter, one or the other official must attend 50 as the voting proceeds, and with his wrench E raise the lid 5 and operate the mechanism described.

I would have it understood that my invention is not limited to the particular style, 55 design or arrangement of parts hereinabove described, as for example, instead of the T-shaped wrench E any other suitable form of device for turning the shafts 6-6^x may be used. Other modifications may be made 60 without departing from my invention, and will be comprehended within the scope and spirit thereof, as set forth in the claims here-to appended.

I do not herein make claims to a counting device operatively actuated by the same means which actuates the hinged lid and the rollers, herein illustrated and described, as I intend to cover this part of my invention in another application.

I claim—

1. A ballot box provided with a ballot receiving aperture in one side, a hinged lid for said aperture, a pair of feed rollers within the box adjacent to the aperture, and an operating element for actuating both the rollers and the hinged lid.

2. A ballot box provided with a ballot receiving aperture in one side, a hinged lid for said aperture, a pair of feed rollers within the box adjacent to the aperture, and means for actuating said rollers and said hinged lid by one operating element, said means including a pawl and ratchet to prevent the reverse rotation of said feed rollers.

3. A ballot box provided with a ballot receiving aperture, a hinged lid for the aperture, feed rollers within the box adjacent to said aperture, and means for operating the hinged lid to uncover the aperture, for rotating the feed rollers to receive and feed a ballot into the box and then for closing the hinged lid over the aperture, said means being actuated by one operating element.

4. A ballot box provided with a ballot receiving aperture, a hinged lid for the aperture, a pair of rotatable shafts within the box, means for actuating said shafts from the outside of the box, a feed roller 100 on each shaft, and operative connections between the shafts and the hinged lid to uncover the aperture, to rotate the feed rollers to receive and feed a ballot into the box and to close the hinged lid over the 105 aperture, said operative connections being actuated from either one of the feed roller shafts.

5. A ballot box provided with a ballot receiving aperture in one side, a hinged lid for said aperture, a pair of feed rollers within the box adjacent to the aperture, means for actuating said rollers and said hinged lid by one operating element, and a yielding detent to lock the feed rollers from 110 rotation after the hinged lid has again closed said aperture.

In testimony that I claim the foregoing as my invention, I affix my signature, in the presence of two witnesses, this 7th day of 115 January, 1924.

JOHN HENRY BARTELS.

Witnesses:
